UNITED STATES PATENT OFFICE.

ANDREW LITTLE, OF NEW YORK, N. Y.

DESIGN FOR TYPE.

Specification forming part of Design No. 5,450, dated December 26, 1871.

To all whom it may concern:

Be it known that I, ANDREW LITTLE, of the city, county, and State of New York, have originated and produced a new and original Design for Printing-Type, of which the following is a specification:

The nature of my design is fully shown in the accompanying typographic impressions, to which reference is had.

What I claim as new, and desire to secure by Letters Patent, is—
The design for printing-type, as shown.

ANDREW LITTLE.

Witnesses:

A. SIDNEY DOANE,
Wm. HASTINGS.
